FOUNTAIN BRUSH AND TUBE HOLDER

Ernest L. Hollenbeck, Los Angeles, Calif.

Application June 2, 1937, Serial No. 145,973

7 Claims. (Cl. 15—135)

My invention relates to fountain brushes and collapsible tube holders of the character embodied in my co-pending application Serial Number 66,580 filed March 2, 1936, now Patent 2,133,295.

It is the purpose of my present invention to provide an improved form of tube holding frame characterized by its ability to embrace a collapsible tube at a plurality of points circumferentially so as to not only prevent lateral or transverse movement of the tube with respect to the brush, but to permit a more careless handling of the device as a whole without the possibility of the tube being unintentionally squeezed and paste expressed into the brush. The frame is further characterized by providing a more simple form of means for latching the frame parts in tube embracing position and to simplify the unlatching operation when desiring to insert a new tube.

It is also a purpose of my invention to provide a new form of tufted brush which is characterized by the provision of tongues bendable to secure bristles in tufted form and without the necessity of employing fastening wires, cement, or any other additional bristle securing means, thus simplifying its construction and materially lowering the cost of manufacturing.

A further purpose of my invention is the provision of a valve characterized by being self-closing and opening only by applying the necessary pressure to the paste contained in the tube, thus eliminating completely the use of a manually operable valve as in my prior device.

Still another purpose of my invention is the provision of a fountain brush and collapsible tube holder wherein the brush head is so constructed as to permit direct mounting of the frame and collapsible tube on the brush and to thereby eliminate intermediate parts, all to the end of reducing the cost of manufacture of the device as a whole.

I will describe only one form of fountain brush and collapsible tube holder embodying my invention and will then point out the novel features thereof in claims.

In the accompanying drawing:

Fig. 1 is a view showing in side elevation one form of fountain brush and collapsible tube holder embodying my invention.

Fig. 2 is an enlarged longitudinal sectional view taken on the line 2—2 of Fig. 1.

Fig. 3 is a transverse sectional view taken on the line 3—3 of Fig. 2.

Fig. 4 is a view similar to Fig. 3 taken on the line 4—4 of Fig. 2.

Fig. 5 is a detail view showing the outer mem-

ber of the brush head in side elevation and before the tongues have been bent into bristle gripping position.

Fig. 6 is a detail view showing the paste feed member in end elevation and the valve thereof closed.

Fig. 7 is a view similar to Fig. 6 showing the valve in open position.

Referring specifically to the drawing, my invention in its present embodiment comprises a fountain brush including a metal head made up of an outer member A of cupped form and an inner member B of tubular form and received in the outer member. As best shown in Figs. 2 and 5, the outer member comprises an annulus 15 formed integral with a base 16, the latter being provided with a central opening formed with a collar 17 which is interiorly threaded as shown. At the junction of the base and annulus the metal is struck at two diametrically opposite points to form two pairs of sockets 18, while between each pair of sockets the annulus is formed with openings 19. On that edge of the annulus 15 opposite the base 16 the former is provided with an annular series of tongues 20 which are tapered and normally disposed in the plane of the annulus, as shown in Fig. 5. These tongues are adapted to be bent inwardly to assume positions at right angles to the annulus, as illustrated in Figs. 2 and 4, to secure bristles 21 in tufted form within the brush head.

The inner member B comprises a metal tube 22 formed at its inner end with an annular flange 23, which seats against the inner walls of the sockets 18 and forms a flat abutment for the inner ends of the bristles 21.

A paste feeding element formed of elastic or similar material is incorporated in the brush for controlling the feed of paste from the collapsible tube to a point centrally of the bristles of the brush. This element comprises a tube 24 extending through the tube 22 and provided at its inner end with a collar 25 interposed between the flange 23 and the base 16. This collar 25 is of considerable thickness and it is so shaped as to accommodate the threaded collar 17. The other end of the tube 24 extends centrally into the bristles 21 with its outer end constructed to provide a valve V which is characterized by being normally closed to prevent leakage of paste therefrom, but is adapted to be automatically opened when the paste within the tube 24 is subjected to sufficient pressure.

The present construction of the valve V is best illustrated in Figs. 2, 6 and 7 wherein it

will be seen that the valve is formed by so moulding the rubber that the tube is provided at spaced intervals circumferentially thereof with exterior and longitudinal indentations or folds 5 26 increasing in depth as they proceed to the free end of the tube. These indentations or folds provide interior projections 27 having bevelled inner ends 27^a and intervening slits 28.

By constructing the valve in this manner the 10 elasticity of the rubber is utilized to urge the projections into contact with each other and to close the slits 28. Thus, the valve is normally closed to prevent discharge of paste therefrom into the brush. In the valve the urging action 15 of the rubber is such that the slits 28 are opened by applying sufficient pressure to the paste contained within the tube, the paste engaging the inner ends 27^a of the projections to force the latter apart and thus open the slits.

20 Manifestly, the decreasing depth of the indentations or folds 26 also lends a tapered form to the exterior of the tube to allow a more intimate association of the bristles in the center of the brush to reduce the possibility of paste being 25 accidentally expelled from the brush.

As shown in Fig. 2, a conventional collapsible paste-containing tube T having the usual nozzle 29 is adapted to be detachably secured to the brush head by screwing the nozzle into the collar 30 17 to compress the rubber collar 25 so that an effective paste seal is formed between the two. Thus the nozzle is placed in communication with the feed tube 24. A conventional key 30 is mounted on the closed end of the tube T for 35 the purpose of compressing the tube through rotation thereof, to expel the paste from the tube into the brush.

For the purpose of holding the tube T against 40 unscrewing from the collar 17 and at the same time to secure the tube fixedly in axial alignment with the feed tube 24, and yet allowing rolling of the tube upon itself through manipulation of the key, I provide a frame which is made up of three parts 31, 32 and 33 separable to permit the ready attachment and detachment of a 45 paste tube to and from the brush head to allow an empty tube to be replaced by a filled tube when and as required. The frame parts 31 and 32 are identical in construction and each is made from a single length of wire bent in the form of 50 a U with its free ends terminating in pins 34 which engage within the sockets 18 in the manner illustrated in Fig. 3 to pivotally support the frame parts on the brush head. At their free or 55 bight ends the frame parts 31 and 32 are bent inwardly so that in closed position they contact with each other.

The third frame part 33 is likewise constructed 60 from a single length of wire, of less gage, however, than the frame parts 31 and 32, and similarly, the ends of this frame part are bent to form pins 35 extending into the openings 19 to pivotally mount the frame part upon the brush head.

To releasably secure the frame parts in closed 65 position, that is, in a position in which the tube T is embraced by the frame parts to securely hold it against any lateral bending movement with respect to the brush head, as well as to prevent unscrewing movement of the tube from 70 the head, keeper notches 36 are formed in the bight portions of the frame parts 31 and 32, while the bight portion of the frame part 33 is bent in the form of a U to provide latch-lugs 37 engageable within the notches 36.

75 Manifestly, when the lugs are within the

notches the frame part 33 secures the frame parts 31 and 32 in closed position, while the notches in turn releasably secure the frame part 33 against swinging movement. In this manner the parts of the frame are securely latched in closed 5 position, and yet by exerting sufficient lateral force on the frame part 33 the lugs 37 can be removed from the notches 36 to swing the frame part to one side to the other, thereby releasing the frame parts 31 and 32 to permit complete 10 opening of the frame when it is desired to insert or remove a paste tube.

A frame constructed as described not only embraces the paste tube to hold it in fixed alignment with the brush head, but, by virtue of the 15 numerous wire strands comprised in the frame situated as they are at intervals circumferentially of the tube and embracing the tube, there is provided the added advantage of reducing the possibility of the tube being accidentally compressed 20 or the user from squeezing the tube thereby inducing him to use the key 30 as intended to feed paste into the brush in the proper quantities. It will be understood that through operation 25 of the key sufficient pressure is built up upon the paste contained therein to expel it into the tube 24 and open the valve so that it may pass into the center of the brush bristles. Manifestly, once the paste is relieved of pressure by opening 30 of the valve, the valve automatically closes to maintain the paste sealed in the feed tube against hardening.

An important feature of my invention is the construction of the brush, for irrespective of whether or not it is used as a fountain brush it 35 will be clear that its construction is such as to render it adaptable to any dauber type of brush. By means of the tongues 20 the bristles 21 are pinched or gripped between any two adjacent tongues to such a degree of security as to eliminate use of any other fastening means such as 40 glue, cement, wire or the like, to maintain the bristles permanently within the head. In addition the bristles are secured in tufted form to minimize the accumulation and hardening of 45 paste, paint or any other substance, and to permit ready cleaning of the brush. Also, depending upon the degree of taper of the tongues 45 determines the degree of spread of the brush as a whole, for it will be clear that as the tongue taper 50 decreases or increases the spread of each tuft is correspondingly decreased or increased.

I claim:

1. Means for holding a collapsible tube on a fountain brush head, comprising a three part frame; two parts of which are adapted to be pivoted on said brush head to swing about parallel axes, and the other part pivoted on said brush head to swing about an axis at right angles to the axes of the other two parts, said two parts at their free ends bent to have contact with each other when the parts are in closed position, and formed with notches, and the said other part formed at its free end with a latch having lugs engaging within the notches for releasably securing the three parts against relative movement.

2. In combination; a brush head comprising an outer member having an annulus, a base formed with a central opening, a collar on the wall of the opening, two pairs of sockets in the outer member at the junction of the annulus and base; an inner member including a tube axially within the outer member, and a flange abutting said sockets; bristles extending into the outer member, around said tube and against said flange; tongues 75

- on the outer member for securing the bristles within the outer member; a feed member having a tube extending through the tube of the inner member and between the bristles, and a collar 5 between the base and the flange.
3. A valve of the character described, comprising; a tube of elastic material having one end indented longitudinally at circumferentially spaced intervals; intersecting slits between the indentations normally closed but adapted to be opened to the respective end of the tube under pressure applied to a fluid contained in the tube, so that such fluid is expelled only from the end of the tube. 10
- 15 4. A valve of the character described, comprising; a tube of elastic material having at one end interior and circumferentially spaced projections, and terminal slits between the projections to open said end by applying pressure to a fluid contained in the tube to cause such pressure to act against said projections.
5. Means for holding a collapsible tube on a fountain brush head, comprising a three part frame two parts of which are adapted to be pivoted on the brush head to swing about parallel 20 axes, and the other part pivoted on the brush head to swing about an axis at right angles to the axes of the other two parts, and coating means on the frame parts for latching all of the frame parts against relative movement. 25
6. A method of securing bristles in tufted form in a brush head having bendable and tapered tongues, which comprises extending the bristles lengthwise into the brush head while the tongues are disposed axially of the head, and then bending the tongues inwardly of the head so that they are extended transversely between the bristles to divide the latter into tufts and cause adjacent tongues to clamp the tufts against lengthwise displacement from the head. 10
7. A method of securing bristles in a brush head having bendable tongues, which comprises extending the bristles lengthwise into the brush head while the tongues are in a non-obstructing position with respect to such inward extension 20 of the bristles, and then bending the tongues inwardly so that they are positioned transversely between the bristles. 15
